UNITED STATES PATENT OFFICE.

GEORGE C. KLEIN, OF LITTLE ROCK, ARKANSAS.

DESIGN FOR A SCORE BOARD FOR A GAME.

Application filed December 1, 1928. Serial No. 29,080. Term of patent 7 years.

To all whom it may concern:

Be it known that I, GEORGE C. KLEIN, a citizen of the United States, residing at Little Rock, in the county of Pulaski and State of Arkansas, have invented a new, original, and ornamental Design for a Score Board for a Game, of which the following is a specification, reference being had to the accompanying drawing, forming part thereof.

In the drawing the figure is a plan view of the score board for a game, showing my new design, the article being of no appreciable thickness.

I claim:

The ornamental design for a score board for a game, as shown and described.

In testimony that I claim the foregoing as my own, I have hereunto affixed my signature.

GEORGE C. KLEIN.
